ATTORNEY

UNITED STATES PATENT OFFICE.

LOUIS PRICE, OF BROOKLYN, NEW YORK.

DESIGN FOR A PIN-POINT PROTECTOR.

52,290.

Specification for Design.

Patented Aug. 20, 1918.

Application filed April 13, 1917. Serial No. 161,912. Term of patent 3½ years.

To all whom it may concern:

Be it known that I, LOUIS PRICE, a citizen of the United States, residing at Brooklyn, in the county of Kings and State of New York, have invented a new, original, and ornamental Design for a Pin-Point Protector, of which the following is a specification, reference being had to the accompanying drawing, forming part thereof.

Fig. 2 is a plan view of a pin point protector, showing my new design.

I claim:

The ornamental design for a pin point protector, as shown.

LOUIS PRICE.

Witnesses:

SAMUEL PRICE,
HERMAN BENDER.
